United States Patent Office

Des. 175,321
Patented Aug. 9, 1955

175,321

SPECTACLE CASE OR THE LIKE

Raymond F. E. Stegeman, Greece, N. Y., assignor to Bausch & Lomb Optical Company, Rochester, N. Y., a corporation of New York

Application September 2, 1954, Serial No. 32,146

Term of patent 7 years

(Cl. D57—1)

FIG. 1

FIG. 2

FIG. 3

FIG. 5

Fig. 1 is a front elevational view of a spectacle case or the like, showing my new design.

Fig. 2 is a rear elevational view of same.

Fig. 3 is an elevational view of the edge thereof as seen from the bottom in Fig. 1.

Fig. 4 is a similar view as seen from the top in Fig. 1.

Fig. 5 is an elevational end view of same as seen from the left side of Fig. 1.

I claim:

The ornamental design for a spectacle case or the like, substantially as shown.
